UNITED STATES PATENT OFFICE

2,031,789

ACOUSTIC ELECTRIC ENERGY CONVERTER

George Washington Pierce, Cambridge, Mass.

Application August 9, 1932, Serial No. 628,042

9 Claims. (Cl. 179—110)

The present invention relates to devices for converting or translating acoustic into electric energy and vice versa, such as loud speakers, and more particularly to devices of this character 5 operable by magnetostrictive action.

A chief object of the invention is to provide a 10 loud speaker operable by magnetostrictive action. Other objects will be explained hereinafter, and will be particularly pointed out in the appended 15 claims.

The term "loud speaker" is used herein to denote a device for delivering sound with sufficiently faithful quality and sufficient intensity to be heard throughout a room. The device of the 20 present invention yields acoustic energy of essentially the same magnitude as the other types of loud speakers now on the market and the quality may be made essentially as good.

It will, therefore, be understood that the term 25 "loud speaker", as used herein, is not properly applicable to an ordinary telephone receiver that is designed to be held to the ear. A telephone receiver, if driven with enough power to raise the intensity to loud-speaker proportions, is defective 30 in quality. It has heretofore been proposed to operate telephone receivers and other acoustic devices magnetostrictively. But none of the prior-art proposals, so far as known, have been even remotely serviceable as loud speakers. The 35 reasons for this are discussed more at length in Letters Patent of the United States No. 1,882,401, granted Oct. 11, 1932.

A magnetostrictive vibrator resonator comprises a magnetostrictive core disposed in an electromagnetic field, such as may be established by 40 passing an electric current through a field coil or winding. The core may be in the form of a rod or tube, or any other desired form. Any ferro-magnetic or other metal having suitable 45 properties may be used for the core, but the material should obviously be characterized by comparatively large or strong magnetostrictive effects or qualities and comparatively low vibrational decrement. The core may be constituted 50 of a bimetallic bar (not shown) made up of two bars of different magnetostrictive materials and welded together throughout their length along their adjoining surfaces, as described in Letters Patent of the United States No. 1,882,399, granted Oct. 11, 1932.

When stimulated magnetically by the field, the core becomes very slightly mechanically deformed or distorted by magnetostriction. The resulting 55 increment of deformation may be a lengthening expansion or a shortening contraction, or some

other distortion, depending on the material and on the polarity of the increment of the magnetic field. This action of the magnetic field upon the core will, for brevity, be hereinafter termed "stimulation". Conversely, when the vibrator is mechanically deformed or distorted, it will react magnetically upon the magnetic field by magnetostriction, with an increment of magnetization depending upon the nature of the preexisting magnetic field and the mechanical deformation, and this will produce its effect upon the electric current or voltage in the coil. This reaction will, for brevity, be hereinafter referred to as the "response".

If the current or voltage is alternating, the 15 electromagnetic field created thereby will also be alternating. The core will, therefore, increase and decrease in length, let us say, many times a second, every variation in the current producing its stimulative effect on the core, and every 20 deformation of the core producing its reaction response upon the current. The core will, in consequence, vibrate mechanically by magnetostriction. Ordinarily, these vibrations will be quite small. When the alternating frequency is 25 varied so as to assume a value close to, or substantially the same as, the natural frequency of mechanical vibration of the vibratory system, however, the amplitude of vibration of the core, though still small, becomes relatively quite large. 30 The core will then react inductively on the load to render its consumption of power critical as to frequency for frequencies near the free frequency of the system.

The invention will be explained in greater detail in connection with the accompanying drawing, in which Fig. 1 is a diagrammatic view of circuits and apparatus arranged and constructed in accordance with a preferred embodiment of the present invention, illustrating a loud speaker; 40 and Fig. 2 is a similar view of a modification.

A magnetostrictive core 2, longer than it is wide, is rigidly secured, as by integral attachment, at its lower end, to a base 13, Fig. 1, which may be in the form of a mass having substantial 45 inertia. The magnetostrictive core is axially positioned within, and driven by, a solenoid field coil or helical electromagnetic winding 24, with clearance to permit free vibrations. The winding 24 is arranged longitudinally of, and around, the 50 core 2 and encircles it for the greater part of its length, as illustrated. For loud-speaker or other reception or sound-reproducer purposes, the coil 24 may be connected in the alternating-current output circuit of a suitable, audible-frequency, 55

sound amplifier, such as a vacuum tube 30, say of a radio-receiving set, or in any other desired way. For transmission purposes, the coil 24 may, on the other hand, be connected in the input circuit of the tube 30. The plate 28 of the vacuum tube is shown connected to the coil by a conductor 12, and the filament 26 by a conductor 14, in series with a local battery 18. The grid 32 and the filament 26 are shown in circuit with the secondary coil 40 of a transformer, the primary coil of which is indicated at 42. The tube 30 constitutes a source of alternating electromotive force or current for the solenoid 24, to enable the latter to drive the magnetostrictive core 2. The winding 24 may be fed at, or substantially at, the natural frequency of the system, as before explained, to get the most pronounced effect.

The battery 18 may serve also to apply a steady magnetizing or polarizing field to the core 2, over which the alternating field produced by the generator 30 is superposed. The alternating field is preferably smaller than the steady field, in order that the combined field may not at any time fall to zero. Polarization may be effected in other ways also, as described in the said Letters Patent of the United States No. 1,882,401, and in Letters Patent of the United States No. 1,750,124, granted March 11, 1930, where the theory of the operation is also described in greater detail.

Thus, the battery may be dispensed with, and the core may be magnetized electromagnetically by a local source sending a polarizing current through a separate polarizing coil, or it may be permanently magnetized, instead, if the vibrator has sufficient magnetic retentiveness, or the battery and a permanently magnetized rod may be employed together. In particular, the magnetization or polarization of the core 2 may be produced by a strong, permanent magnet of substantially constant, relatively large or intense magnetic field of predetermined strength, supported near the vibrator, as hereinafter described, and it may have magnetostrictive qualities opposite to those of the core 2.

The operation will be better understood by the following example: Nickel is a magnetostrictive material that shortens with an increase of magnetization. The shortening or static magnetization is very minute. If, however, it is polarized by an applied steady field, upon which is superposed an alternating current resonant with its natural frequency of mechanical vibration, it becomes specifically treated to increase its lineal or other magnetostrictive displacement, and its amplitude of length variation may become several hundred times as great as with static or non-resonant magnetization.

The upper end of the core 2 is shown connected with a loud-speaker, sound-radiating member or diaphragm 68, or with some other sound-radiating or receiving member, as will be understood by persons skilled in the art.

According to the modification of Fig. 2, the radiating diaphragm 68 may, for example, be constituted of a wooden board or a metal sheet, attached to any desired support. The said upper end of the core 2 is shown attached to the diaphragm 68 by a crow foot or spider 75. The spider 75 serves to extend the attachment of the core to a larger area of the diaphragm 68, which permits a better path for transmission of sound vibrations. The function of the weighted mass 73 is described in the said Letters Patent 1,882,401.

According to the modification of Fig. 2, furthermore, permanent magnets or ferro-magnetic

bars 91 are attached at one end, as by means of bolts 93, to the inertia member 73 and extend upwardly from their attaching points throughout substantially the length of the core 2. The crow foot or spider 75 may then preferably be made of iron, and small air gaps 95 may be provided between the ends of the spider and the ends of the bars 91 to permit free vibration of the radiating face 68.

In Fig. 1, the core 2 and weighted end are substantially as before described, but the winding 24 is surrounded by, and arranged within the magnetic field of, an elongated frame member or housing 97. As the housing 97 is double-U-shaped in cross section, it encircles, and is spaced slightly from, and longitudinally of, the core 2. The housing 97 may, if desired, be a magnet or be constituted of magnetic material, and be used for polarizing the core 2. The opposite poles of the magnet are disposed opposite to the ends of the core 2, the pole at the lower limb 104 of the magnet 97 being in magnetic contact with the core 2 at its lower, rigidly fixed extremity and the pole at the upper limb 106 of the magnet 97 being in close proximity to, but out of engagement with, and encircling, the core 2, as illustrated. A return magnetic path is thus provided for the magnetic flux in the core 2 with a minimum air gap. The magnet should obviously be of such strength as to premagnetize the core 2 to that point on the magnetostrictive core 2 corresponding to its most efficient point of sensitivity to magnetostrictive variations. A lever 98 is pivoted to the frame 97 at 99 and bears upon the free end of the core 2. The arms of the lever 98 are unequal in length, as shown. The core impedance is thus so adapted to the diaphragm impedance as to make possible the use of a less massive diaphragm.

Variations in the current in the electromagnet 40 winding 24 will react upon the magnetic field to cause undulatory changes in the magnetic flux of the core 2, thus producing correspondingly opposite magnetostrictive-effect variations or changes in the lineal or other dimensions of the core 2 and in the winding 24, cumulative in their effect to reproduce voice sounds by vibrating the diaphragm 68. At, or substantially at, the natural frequency of the system, the reaction of the magnet 97 on the core 2 is periodically varied to a maximum extent, as before described, so as to produce a maximum effect in the loud speaker.

The mass attached to the non-radiating end of the core may be about ten pounds. The radiator may be a plane wooden board, about 1 to 2 inches thick, preferably more than one inch thick, and may have an area of 8 to 100 or more square feet, but other shapes of radiating members may be used, as before described, characterized by graduated stiffness, density or speed. Where the radiator is curved or in the form of a cone, the thickness should correspond to the increase of stiffness of the curved or conical surface.

The invention is not, of course, limited to the modifications illustrated herein, and may be further modified and changed by persons skilled in the art without departing from its spirit and scope, as defined in the appended claims.

What is claimed is:

1. In a sound reproducer, a metallic rod having strong magnetostrictive qualities, an electro-magnetic coil encircling said rod and spaced slightly therefrom, a strong permanent magnet arranged with opposite poles thereof opposite different ends of the rod, a clamping means rigid-

ly securing one end of the rod, and a diaphragm connected to the opposite end of the rod, said coil when connected to alternating current being effective to vibrate the diaphragm in accordance 5 with the current.

5. In a sound reproducer, a vibratory member, an actuating element for the member constructed of ferro-magnetic metal having strong magnetostrictive qualities, said element being rigidly secured at one end and being attached at the other end to the vibratory member, a permanent magnet of relatively large and predetermined strength arranged longitudinally to said element, said magnet premagnetizing said element substantially to its most efficient point of sensitivity 10 to magnetostrictive variations, and a helix or electromagnetic coil encircling said element for the greater part of its length, said helix being adapted to be connected to a source of alternating current to cause corresponding lineal expansion and contraction of said element, thereby to vibrate said member.

6. In a sound reproducer, a ferro-magnetic member, an elongated U-shaped permanent magnet of predetermined strength, said member being longitudinally supported in the magnetic field of said permanent magnet, one pole of the magnet not being in magnetic contact with the member at one rigidly fixed extremity, the other pole 20 being in close proximity but out of engagement with the member, thereby providing a return path for magnetic flux in the member with minimum air gap, a diaphragm connected to one end of the member, and an electromagnetic coil associated 30 with the member connected with the output of a suitable audible-frequency sound amplifier, said electromagnetic coil causing undulations of the magnetic flux in said member and corresponding changes in lineal dimensions of the member, thereby to reproduce voice frequency sounds by vibrating the diaphragm.

7. In a sound reproducer, a diaphragm, a permanent magnet, an operating member for the diaphragm of ferro-magnetic material, said member being rigidly supported and in magnetic contact with one limb of the magnet and having its free end encircled by the other limb of said magnet, and engaging with the diaphragm, and an electromagnetic coil arranged longitudinally to both magnet and member and connected to a source of variable current, variations in current

in the electromagnetic coil causing magnetostrictive effects in the magnet to produce an effect on the diaphragm.

5. In a sound reproducer, a metallic member rigidly secured at one end and attached to a diaphragm at its other end, a magnet arranged longitudinally thereof magnetizing the member, and a helix around said member, said helix being adapted to be traversed by alternating current which causes changes in the magnetic flux in 10 said member to cause corresponding linear expansion and contraction of said member by magnetostrictive effects to vibrate the diaphragm.

6. In a sound reproducer, a metallic member supported in a magnetic field and premagnetized substantially to its most effective point on the magnetostrictive curve, an electromagnetic coil associated with said member and adapted to be connected in the alternating-current output of a vacuum-tube amplifier, and a sound-radiating 15 element coupled to one end of the member, said electromagnetic coil causing undulations in the magnetic flux of said member to cause corresponding changes in the dimensions of said member, thereby to operate the sound-radiating element to emit sound.

7. In a sound reproducer, a diaphragm, a metallic member coupled thereto longer than its own width, a magnet for premagnetizing the member substantially to its highest point of sensitivity to 30 magnetostrictive variation, and an electromagnetic coil for causing changes in the magnetism of said member, thereby to produce changes in length of the member to vibrate the diaphragm.

8. An electro-mechanical resonator operating 35 by magnetostriction comprising in combination a magnet having a substantially constant relatively intense magnetic field, a magnetostrictive vibrator arranged within said field and a coil adapted to be fed with alternating current at or substantially at the natural frequency of said vibrator, whereby alternating current flowing in the coil acts in conjunction with the magnetic field to produce magnetostrictive variations in the dimensions of the vibrator.

9. An electromechanical resonator as claimed in claim 8 and in which the coil fed with alternating current at or substantially at the natural frequency of the vibrator, surrounds said vibrator substantially as described.

45 50
GEORGE W. PIERCE.
